US00D530009S

(12) **United States Design Patent** (10) **Patent No.:** **US D530,009 S**
(45) **Date of Patent:** **** Oct. 10, 2006**

(54) **SYRINGE TOOL**

(75) Inventors: **Scott D. Lyman**, Oak Park, CA (US);
B. Cameron Smith, Seattle, WA (US)

(73) Assignee: **Amgen Inc.**, Thousand Oaks, CA (US)

(**) Term: **14 Years**

(21) Appl. No.: **29/201,408**

(22) Filed: **Mar. 15, 2004**

(51) **LOC (8) Cl. 24-02**

(52) **U.S. Cl. D24/129; D24/108; D24/130**

(58) **Field of Classification Search D24/134,
D24/112, 108, 130, 129; 81/3.07; 604/416,
604/905**

See application file for complete search history.

(74) *Attorney, Agent, or Firm*—Marshall, Gerstein & Borun LLP

(57) **CLAIM**

The ornamental design for a “syringe tool,” as shown and described.

DESCRIPTION

FIG. 1 is a front quarter perspective view showing a first disclosed example of my new design;

FIG. 2 is a rear quarter perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a front quarter perspective view showing a second disclosed example of my new design;

FIG. 10 is a rear quarter perspective view thereof;

FIG. 11 is a right side elevational view thereof;

FIG. 12 is a left side elevational view thereof;

FIG. 13 is a front elevational view thereof;

FIG. 14 is a rear elevational view thereof;

FIG. 15 is a comp plan view thereof; and,

FIG. 16 is a bottom plan view thereof.
